UNITED STATES PATENT OFFICE.

JAMES WALSH, OF PORTLAND, OREGON.

DESIGN FOR AN ELECTRIC-LIGHTING FIXTURE.

45,210.

Specification for Design.

Patented Feb. 3, 1914.

Application filed July 29, 1913. Serial No. 781,884. Term of patent 3½ years.

To all whom it may concern:

Be it known that I, JAMES WALSH, a citizen of the United States, residing at Portland, in the county of Multnomah and State of Oregon, have invented a new, original, and ornamental Design for an Electric-Lighting Fixture, of which the following is a specification, reference being had to the accompanying drawing, forming part thereof.

The figure is a side elevation showing my

new design the fixture being horizontally round.

I claim:

The ornamental design for an electric lighting fixture as shown.

JAMES WALSH.

Witnesses:

ROBT. W. LARSEN,
J. W. OBERENDER.
